UNITED STATES PATENT OFFICE.

CHARLES FOWLER, OF BOSTON, MASSACHUSETTS.

STOCKING-STRETCHER.

1,401,065.

Specification of Letters Patent. Patented Dec. 20, 1921.

Application filed June 22, 1920. Serial No. 390,912.

To all whom it may concern:

Be it known that I, CHARLES FOWLER, a citizen of the United States, residing at Boston, in the county of Suffolk and State 5 of Massachusetts, have invented new and useful Improvements in Stocking-Stretchers, of which the following is a specification.

This invention relates to improvements in stocking stretchers.

10 The primary object of the invention is to provide for a comparatively simple and inexpensive construction of the character mentioned, and one in which the foot as well as the leg portion of a stocking is expanded 15 and stretched laterally in all directions rather than in a transverse direction from front to rear as has heretofore obtained in the art to which the same relates.

With this and other objects in view as will 20 be readily apparent as the invention is further explained, the same resides in the certain novel construction and arrangement of parts as will be hereinafter more fully described, set forth in the appended claims, 25 and illustrated in the accompanying drawing, in which:

Figure 1 is a perspective view of the preferred embodiment of the invention, and

Fig. 2 is a side elevation thereof.

30 Referring to the drawing, the invention, as shown, is preferably constructed entirely of a suitable sized wire, but the same may readily be similarly formed of other material such as strap iron, hoop wood, or the 35 like, and, in any case, the same comprises in general a foot portion *a*, a heel portion *b* and an ankle portion *c*.

In the present instance, the device is 40 constructed wholly of wire, and in the embodiment shown, the foot and heel portions *a* and *b* are formed of a single piece of wire bent on curved lines to form a toe stretching portion 10, an intermediate toe stretching portion 11, intermediate heel stretching portions 12 and a heel stretching end portion 13, all curving one into the other and conforming generally to a contour outline of the foot of a person. The portions 11 and 45 12, at opposite sides of the device are bent at their point of connection or juncture to provide eyes 14 in transverse alinement, while the free ends of the single piece of wire forming the toe and heel portions *a* and *b*, in their entirety, are suitably bent 50 and twisted into interlocked engagement, 55 one with the other to either side of the cen-

ter of the heel portion 13, and in a manner to provide an eye 15 at the center of the latter.

The ankle portion *c* comprises a single 60 piece of wire bent on a curved line, and substantially U-shaped, inverted as shown, the opposite arms 16 of which having their free ends bent to provide eyes 17 in loose or hinging engagement with the eyes 14 of 65 the toe and heel portions *a* and *b*, and, when the device is not in use, this ankle portion *c* may be folded down onto the heel portion *b*. Medially of the curved portion of the 70 ankle portion *c*, the wire is bent to form 75 an eye 18, the same being adapted to be engaged by a hooked end portion 19 of a supporting element or brace member 20, also made of wire, and having its lower end bent to provide an eye 21 in hinging en- 75 gagement with the eye 15 of the heel portion *b*, the brace member 20 being adapted to retain the ankle portion *c* in its raised position, when the device is in use.

In its use, the device may be inserted into 80 the foot portion of a sock or stocking in either set-up or collapsed condition, and in the latter case, the ankle portion *c* is lifted to raised position and the hook 19, of the 85 brace member 20, engaged in the eye 18, and, in either case, the toe and heel portions *a* and *b* will expand or stretch the foot portion of the sock or stocking laterally in all directions, while the ankle portion *c* will retain and hold the ankle portion of the sock 90 or stocking in raised, or partly raised position and free from the foot portion of the same. The device may be used simply as a 95 sock or stocking expander, or as a stretcher in the drying of the latter as after the same have been washed. It is to be noted that even when a sock or stocking has been 100 properly ironed for use, the device may be inserted into position for expanding or stretching action, and subsequently removed without destroying the ironed effect thereof.

It is also contemplated in the manufacture of this device that the brace member 20 may be entirely dispensed with, together with the eye 15, of the heel portion *b*, and the 105 eye 18, of the ankle portion *c*, in which case, the latter is to be secured to the eyes 14 of the toe and heel portions *a* and *b* in a manner to be held in permanent raised position, or other suitable means being utilized for 110 such purpose.

It is well understood that various changes

in specific construction and arrangement, and materials used, may be resorted to, as hereinbefore indicated, without departing from the spirit and scope of the invention.

Having thus fully described the invention, what I claim, is:—

1. A device of the character described comprising an open frame having substantially the shape of the human foot and embodying a toe portion and a heel portion, a bail-shaped member having its arms connected to the sides of said frame at or about the points of intersection of said toe and heel portions, and a brace member for connecting the bight portion of said bail-shaped member with the bight of the heel portion of the frame.

2. A device of the character described comprising an open frame having substantially the shape of the human foot, said frame embodying a toe portion and a heel portion, a bail-shaped member having its arms pivotally connected with the sides of the frame at or about the points of intersection of said toe and heel portions, whereby said bail-shaped member is adapted to be folded substantially in parallel relation to the frame, and a brace pivotally connected with the bight of the heel portion of the frame and adapted for detachable engagement with the bight of the bail-shaped member for holding said bail-shaped member in an erect position.

3. A device of the character described comprising an open frame formed of wire and having substantially the shape of the human foot, said frame embodying toe and heel portions, a bail-shaped member of wire

having its arms pivotally connected with the sides of said frame at or near the points of intersection of said toe and heel portions, and a brace pivotally connected with the bight of the toe portion and adapted for detachable engagement with the bight portion of the bail-shaped member for holding said bail-shaped member in an erect position and permitting release of said bail-shaped member to adapt it to be folded down upon the frame substantially parallel therewith.

4. A device of the class described, comprising a toe portion and a heel portion integrally formed of a single piece of wire and of a shape approximating the contour outline of the foot of a person, eyes formed in transverse alignment of and intermediate the toe and heel portions, an ankle portion formed of a single piece of wire and having its opposite ends hingedly engaging said eyes, an eye formed medially of the heel portion, a similar eye formed medially of the connected ends of the ankle portion, and a brace member connecting the last mentioned eyes whereby to retain the ankle portion in raised position.

5. A device of the character described comprising an open frame having substantially the shape of the human foot and embodying a toe portion and a heel portion, and a bail-shaped ankle member bridging across said open frame and having its arms connected to the sides of said frame at or about the points of intersection of said toe and heel portions.

In testimony whereof I affix my signature.

CHARLES FOWLER.
